Des. 224,591

Patented Aug. 8, 1972

224,591

EASY BREAK TABLET

Edwin F. Roberts, 319 Woodbine Road,
Stamford, Conn. 06903

Filed Jan. 27, 1971, Ser. No. 110,364

Term of patent 14 years

Int. Cl. D28—01; D1—01

U.S. Cl. D16—1

FIG. 2

FIG. 1

FIG. 3

FIG. 4

FIG. 5

FIG. 6

FIG. 1 is an isometric view of a pharmaceutical tablet embodying my new design;

FIG. 2 is a top plan view thereof;

FIG. 3 is a side elevational view thereof as seen at right angles to FIG. 2;

FIG. 4 is an end elevational view thereof as seen at right angles to FIG. 2;

FIG. 5 is an end elevational view of a pharmaceutical tablet embodying a modification of the form illustrated in FIG. 4;

FIG. 6 is a bottom view of the embodiments of FIG. 1 and FIG. 5.

I claim:

The ornamental design for an easy break tablet, as shown and described.
